Primary Examiner — Rhea Shields(57) **CLAIM**

The ornamental design for an electrical case, as shown and described.

DESCRIPTION

FIG. 1 is a perspective view of an electrical case showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear side perspective view thereof;

FIG. 9 is an enlarged partial view of FIG. 8; and,

FIG. 10 is an enlarged partial view of FIG. 8.

1 Claim, 10 Drawing Sheets**FIG. 1**

FIG. 2

FIG. 3

FIG. 4

FIG. 5

FIG. 6

FIG. 7

FIG. 8

FIG. 9
